UNITED STATES PATENT OFFICE

CLAYTON J. HARVEY, OF BUFFALO, NEW YORK, ASSIGNOR TO JEWELL STEEL & MALLEABLE CO., OF BUFFALO, NEW YORK, A CORPORATION OF NEW YORK

ANCHOR

Application filed June 27, 1932. Serial No. 619,396.

This invention relates to improvements in anchors of the kind which include an elongated shank to which the hauling line is connected. More particularly the invention is concerned with an anchor of the type in which the connection between the hauling line and the anchor is through the medium of a runner which is loosely mounted upon the shank and which is movable thereon, as occasion may require, to either of two positions, in one of which engagement of the flukes of the anchor is facilitated and in the other of which disengagement of the flukes is facilitated.

Heretofore it has been the practice to construct the anchor in such a manner that the runner is free to move in either direction, the shank owing to its weight overbalancing the anchor when the runner is in the position at which the force which is applied to the hauling line can be most effectively transmitted to the anchor.

It frequently, however, happens that owing to the firmness with which the flukes are engaged or embedded, it is necessary to apply a greater force to the hauling line than is normally necessary. The resistance to disengagement which is thus offered by the anchor is, in many instances, greater than can be overbalanced by the shank. The free end 30 of the latter, therefore, moves toward a vertical or upright position thereby permitting the runner to move away from the position in which it must remain in order to facilitate disengagement of the flukes. The purpose of the runner is thus defeated.

The principal object of the present invention is to overcome the above objection, this object contemplating the locking of the runner at that point on the shank at which the force which is applied to the hauling line can be most effectively transmitted to the anchor.

The invention is illustrated in the accompanying drawing in which:

Figure 1 is a side elevation of an anchor embodying features of the invention.

Figure 2 is a top view of the anchor.

Figure 3 is an enlarged fragmentary section taken along line 3-3 of Figure 2.

Figure 4 is a fragmentary section taken along line 4-4 of Figure 3.

Figure 5 is an enlarged fragmentary section taken along line 5-5 of Figure 2.

The anchor, as illustrated, includes a body 6 and an elongated shank 7. The former is formed or provided with suitable flukes 8. In order to facilitate engagement of the flukes, the shank 7 is preferably pivotally connected to the body 6 so as to permit the latter, under the influence of gravity, to assume positions at an angle to and at either side of the shank. To this end the shank 7 is formed or provided at one end with a ball 9 which fits loosely within a socket 10 formed in the body, the ball being held in the position described by a pin 11 which is secured at its ends in opposite walls of the socket. The shank 7 extends through an arcuate slot 12 which is formed in the head between the flukes and transversely of the plane occupied by the latter, whereby the body, under the influence of gravity, pivots on the ball 9 and the flukes are presented for effective engagement. The range of movement of the latter is determined by the end walls 13 of the slot 12.

The anchor may be connected to a suitable hauling line 14 (Figure 1) through the agency of a runner 15. The latter includes a clevis 15 which fits loosely upon the shank and which is freely movable thereon between the body 6 and a ball head 17, the latter being formed or provided at the free end of the shank. When the flukes of the anchor are engaged the runner 15 is preferably positioned at the free end of the shank 7, that is to say against, or in the vicinity of, the head 17. The runner is preferably arranged in this manner prior to dropping of the anchor in order to facilitate engagement of the flukes. When weighing anchor the runner is moved until it is arrested by the body 6, that is to say, it is moved from the position shown in dotted lines in Figure 1 to the position shown in full lines. This may be conveniently effected by causing the boat which carries the anchor to move in the direction opposite to that in which it tends to drift.

Heretofore it has been the practice in designing anchors of the type generally described to so balance them that when the run-

- ner moves against or in the vicinity of the head of the anchor and a force normally adequate to free the anchor is applied to the hauling line, the head of the anchor will 5 pivot about its connection with the shank and free itself. It frequently happens, however, that the flukes of the anchor become so firmly engaged or embedded that a greater degree of force than normal is required to free them.
- 10 Hence, in such a case the balance of the anchor is overcome and the free end of the shank is pivoted with respect to the anchor head instead of the latter being pivoted with respect to the shank. The runner, therefore, 15 moves toward the free end of the shank, thereby rendering disengagement of the flukes more difficult, if not impossible.

In order to overcome this objection the invention contemplates the locking of the runner upon the shank in the vicinity of the anchor head so that as the hauling line is drawn in to weigh anchor the runner maintains its position and the head 6 pivots on the ball 9 to free itself despite the degree of 25 force which is required to accomplish this. To this end an element 18 is pivotally mounted between the arms of the clevis 16 upon a pin 19. The element is supported in such relation to the shank that one end thereof 30 may be moved into and out of engagement with the shank. At its opposite end the element 18 carries a ringlike clevis 20 which is pivotally connected to the element by a pin 21 and to which the end of the hauling line 14 35 may be suitably secured. The runner is freely movable upon the shank between the anchor head and the free end of the shank. Hence it may be positioned at the free end of the shank when dropping anchor and when preparing to weigh anchor it can be moved to the 40 opposite end of the shank in the usual manner.

From the foregoing it will be apparent that disengagement of the flukes of the anchor is facilitated despite the degree of force which must be applied to the hauling line to accomplish this, the runner being automatically secured on the shank at the point at which the force that is applied to the hauling line is most effectively transmitted to the anchor.

I claim as my invention:

1. An anchor including a body provided with flukes, an elongated shank, a runner carried by said shank and to which a suitable hauling line may be connected, said runner being freely movable between said body and the free end of said shank and means for locking said runner in the vicinity of said body to prevent it from slipping away from the latter when it is in such position and force is applied to said line to effect disengagement of said flukes.
2. An anchor including a body provided 65 with flukes, an elongated shank, a runner car-

ried by said shank and to which a suitable hauling line may be connected, said runner being freely movable between said body and the free end of said shank and means controlled by said line for locking said runner in the vicinity of said body to prevent it from slipping away from the latter when it is in such position and force is applied to said line to effect disengagement of said flukes. 70

3. An anchor including a body provided with flukes, an elongated shank, a runner carried by said shank, said runner being freely movable between said body and the free end of said shank and an element carried by said runner and to which a suitable hauling line may be connected, said element being adapted to engage said shank and secure said runner against movement when the latter is in the vicinity of said body and force is applied to said line to effect disengagement of said flukes. 75

4. An anchor including a body provided with flukes, an elongated shank, a runner carried by said shank, said runner being freely movable between said body and the free end of said shank and an element pivotally connected to said runner at one end and to the opposite end of which a suitable hauling line may be connected, said element being adapted to engage said shank and secure said runner against movement when the latter is in the vicinity of said body and force is applied to said line to effect disengagement of said flukes. 80

5. An anchor including a body provided with flukes, an elongated shank, a runner carried by said shank, said runner being freely movable between said body and the free end of said shank, an element pivotally connected at one end to said runner and a link connected to the other end of said element and to which a suitable hauling line may be connected, whereby said element is operable to engage said shank and secure said runner against movement when the latter is in the vicinity of said body and force is applied to said line to effect disengagement of said flukes. 85

6. In an anchor having a body provided with flukes and an elongated shank pivotally connected to said body for angular movement within a predetermined range, the combination of a runner carried by said shank and to which a suitable hauling line may be connected, said runner being freely movable between said body and the free end of said shank and means for locking said runner in the vicinity of said body to prevent it from slipping away from the latter when it is in such position and force is applied to said line to effect disengagement of said flukes. 90

7. In an anchor having a body provided with flukes and an elongated shank pivotally connected to said body for angular movement within a predetermined range, the combination of a runner carried by said shank and to 95

which a suitable hauling line may be connected, said runner being freely movable between said body and the free end of said shank and means controlled by said line for locking said runner in the vicinity of said body to prevent it from slipping away from the latter when it is in such position and force is applied to said line to effect disengagement of said flukes.

10 8. In an anchor having a body provided with flukes and an elongated shank pivotally connected to said body for angular movement within a predetermined range, the combination of a runner carried by said shank, said runner being freely movable between said body and the free end of said shank and an element carried by said runner and to which a suitable hauling line may be connected, said element being adapted to engage said shank and secure said runner against movement when the latter is in the vicinity of said body and force is applied to said line to effect disengagement of said flukes.

9. In an anchor having a body provided with flukes and an elongated shank pivotally connected to said body for angular movement within a predetermined range, the combination of a runner carried by said shank, said runner being freely movable between said body and the free end of said shank and an element pivotally connected to said runner at one end and to the opposite end of which a suitable hauling line may be connected, said element being adapted to engage said shank and secure said runner against movement when the latter is in the vicinity of said body and force is applied to said line to effect disengagement of said flukes.

10. In an anchor having a body provided with flukes and an elongated shank pivotally connected to said body for angular movement within a predetermined range, the combination of a runner carried by said shank, said runner being freely movable between said body and the free end of said shank, an element pivotally connected at one end to said runner and a link connected to the other end of said element and to which a suitable hauling line may be connected, whereby said element is operable to engage said shank and secure said runner against movement when the latter is in the vicinity of said body and force is applied to said line to effect disengagement of said flukes.

55 In testimony whereof I affix my signature.
CLAYTON J. HARVEY.
